(57) **CLAIM**

The ornamental design for a phone charger, as shown and described.

DESCRIPTION

FIG. 1 is top, front, and left side perspective view of a phone charger, showing my new design;

FIG. 2 is a front elevation view thereof;

FIG. 3 is a rear elevation view thereof; and

FIG. 4 is a left side elevation view thereof;

FIG. 5 is a right side elevation view thereof;

FIG. 6 is a top plan view thereof;

FIG. 7 is a bottom plan view thereof;

FIG. 8 is a bottom, rear, and left side perspective view thereof; and,

FIG. 9 is a bottom, front, and left perspective view thereof. The broken lines and the light gray surface inside the broken lines form no part of the claimed design.
